CLAIM

The ornamental design for a bird soap, as shown and described.

DESCRIPTION

FIG. 1 is a front perspective view of the bird soap of the present invention showing my new design;

FIG. 2 is a left side elevational view thereof;

FIG. 3 is a front elevational view thereof, the rear view being a mirror image of the front; and,

FIG. 4 is a right side elevational view thereof.

The bottom view follows the configuration and surface appearance of the sides shown.
